PERFUME DISPENSER

William P. Cady, Glendale, Calif.

Application October 24, 1947, Serial No. 142,131

Term of patent 3½ years

(Cl. D83—1)

To all whom it may concern:

Be it known that I, William P. Cady, a citizen of the United States of America, resident of Glendale, in the county of Los Angeles, State of California, have invented a new, original, and ornamental Design for a Perfume Dispenser, of which the following is a specification, reference being had to the accompanying drawing, forming part thereof.

In the drawing,

Fig. 1 is an elevational view of a perfume dispenser showing my new design;

Fig. 2 is a top plan view;

Fig. 3 is a view similar to Fig. 1, but showing the cap and dispenser body separated; and

Fig. 4 is a plan view of the top of the dispenser taken along the line 4—4 of Fig. 3.

I claim:

The ornamental design for a perfume dispenser, as shown.

WILLIAM P. CADY.
